Inventor
Harry E. Osborne
By his Attorney
Thomas J. Ogan.

end of the upper, stitching the inner margin of the welt to the bottom margin of the upper. When the point of operation has advanced to the edge of the opening 10 the operator will glance at the strip 12 to make certain that it has not been misplaced but is in position to receive the stitches 20 as the point of operation advances across the opening 10. Ordinarily this will not involve any interruption in the stitching operation but on the contrary the stitching will proceed with the same speed and facility as though the upper were of the usual closed toe type.

The upper is now lasted and an outsole 22 (Fig. 4) is secured to the welt by stitches 24. At this stage in the manufacture of the shoe that portion of the strip 12 which is visible through the opening 10 should be eliminated or concealed. I prefer to cut out the visible portion of the strip along a line contiguous to the seam 20 but if desired the visible portion of the strip may be folded in and covered by the toe portion of the slip sole or sock lining 26.

While my invention is herein illustrated in its application to the manufacture of prewelt shoes it is to be understood that the invention in certain aspects is applicable to the manufacture of other types of shoes, particularly stitchdowns.

Having thus described my invention, what I claim as new and desire to secure by Letter Patent of the United States is:

1. That method of making shoes which comprises forming an upper with an opening in its bottom margin, said opening being of maximum width at the edge of the upper, contracting said marginal opening to shape the upper, said opening after its contraction still being of substantial width at the edge of the upper, applying a tape to the bottom margin of the upper to connect portions of said upper at opposite sides of said opening, and completing the shoe.

2. That method of making shoes which comprises forming an upper with an opening in its bottom margin, said opening being of maximum width at the edge of the upper, contracting said marginal opening to shape the upper but without closing said opening at the edge of the upper, applying a tape to the bottom margin of the upper to retain the shape imparted thereto, said tape connecting marginal portions at opposite sides of said opening, providing a sole attaching welt for said upper, stitching said welt to the bottom margin of the upper and to said tape, and completing the shoe.

3. That method of making shoes which comprises forming an upper with an opening in its

bottom margin, said opening being of maximum width at the edge of the upper, contracting said marginal opening to shape the upper, said opening after its contraction still being of maximum width at the edge of the upper, applying a tape to the bottom margin of the upper to retain the shape imparted thereto by contracting said opening, said tape connecting marginal portions of the upper at opposite sides of said opening, providing a sole attaching welt for said upper, stitching said welt to the bottom margin of the upper and to said tape, securing a sole to said welt, removing the visible portion of said tape, and completing the shoe.

4. That method of making shoes which comprises forming an upper with a generally semi-circular opening in its bottom margin, contracting said marginal opening to shape the upper, said opening after its contraction still being of maximum width at the edge of the upper, applying a tape to the bottom margin of the upper to retain the shape imparted thereto by contracting said marginal opening, said tape connecting marginal portions of the upper at opposite sides of said opening, providing a sole attaching welt for the upper, stitching said welt to the bottom margin of the upper and to said tape, securing a sole to said welt, turning inwardly that portion of said strip visible through said marginal opening, and arranging a slip sole to cover said inturned portion.

5. That method of making shoes, which comprises forming an upper with a marginal opening therein, contracting said marginal opening to shape the upper, retaining the shape thus imparted to the upper by securing a tape to the inner surface of the upper, said tape being arranged to connect marginal portions of the upper at opposite sides of said opening, providing a sole attaching welt for said upper, stitching said welt to the bottom margin of the upper and to said tape, stitching said welt to a sole, eliminating that portion of said tape visible through the marginal opening in the upper, and completing the shoe.
